[57] CLAIM

The ornamental design for a cover for a telephone handset, as shown and described.

DESCRIPTION

FIG. 1 is a perspective view of a cover for a telephone handset showing my new design, the broken line showing of the push buttons of a telephone handset being for illustrative purposes only;

FIG. 2 is a right end view of the covered handset of FIG. 1;

FIG. 3 is a front elevational view of the covered handset of FIG. 1;

FIG. 4 is a plan view of the underside of the covered handset of FIG. 1;

FIG. 5 is a rear elevational view of the covered handset of FIG. 1; and,

FIG. 6 is a left end view of the covered handset of FIG. 1.

FIG. 1

FIG. 2

FIG. 3

FIG. 4

FIG. 5

FIG. 6
